US00D783290S

(12) **United States Design Patent** (10) Patent No.: **US D783,290 S**
Lee et al. (45) Date of Patent: **** Apr. 11, 2017**

(54) **ORAL CARE IMPLEMENT**

- (71) Applicant: **Colgate-Palmolive Company**, New York, NY (US)
(72) Inventors: **David Kyung Min Lee**, East Brunswick, NJ (US); **Robert Moskovich**, East Brunswick, NJ (US)
(73) Assignee: **COLGATE-PALMOLIVE COMPANY**, New York, NY (US)

(**) Term: **15 Years**

(21) Appl. No.: **29/571,874**

(22) Filed: **Jul. 22, 2016**

Related U.S. Application Data

- (62) Division of application No. 29/471,821, filed on Nov. 5, 2013, now Pat. No. Des. 764,804.
(51) LOC (10) Cl. **04-02**
(52) U.S. Cl. **D4/104**

(57) **CLAIM**

The ornamental design for an oral care implement, as shown and described.

DESCRIPTION

FIG. 1 is a right front perspective view of an oral care implement according to the new design;
FIG. 2 is a left front perspective view thereof;
FIG. 3 is a right rear perspective view thereof;
FIG. 4 is a left rear perspective view thereof;
FIG. 5 is a front view thereof;
FIG. 6 is a rear view thereof;
FIG. 7 is a left side view thereof;
FIG. 8 is a right side view thereof;
FIG. 9 is a top view thereof; and,
FIG. 10 is a bottom view thereof.

1 Claim, 5 Drawing Sheets
